UNITED STATES PATENT OFFICE.

HARRY B. KUNTZ AND GEORGE T. KUNTZ, OF PORT TOWNSEND, WASHINGTON.

WRENCH.

1,094,446.

Specification of Letters Patent. Patented Apr. 28, 1914.

Application filed March 16, 1912. Serial No. 684,265.

To all whom it may concern:

Be it known that we, HARRY B. KUNTZ and GEORGE T. KUNTZ, citizens of the United States, residing at Port Townsend, in the county of Jefferson and State of Washington, have invented certain new and useful Improvements in Wrenches, of which the following is a specification.

This invention relates to wrenches, and 10 has for its object to construct a wrench, the jaws of which may be arranged at any desired angle to the handle thereof and retained in this position through the instrumentality of a ratchet and pawl mechanism.

15 It is further designed to provide a means whereby the movable jaw may be detached, if so desired, from the body of the wrench, and further to provide a means whereby said movable jaw is adjustable independent 20 of the handle.

With the above and other objects in view, this invention consists in the combination, construction and arrangement of parts, all 25 as hereinafter more fully described, claimed and illustrated in the accompanying drawings, wherein:

Figure 1 is a side elevation of a wrench constructed in accordance with the present invention; Fig. 2 is a front elevation thereof; Fig. 3 is a similar view taken opposite to Fig. 1 of the handle structure; Fig. 4 is a side elevation thereof; Fig. 5 is a section taken along line 5—5 of Fig. 1; and Fig. 6 is an inside elevation of the stationary jaw.

35 Referring more particularly to the drawings, 10 indicates a handle cast of one continuous piece of material, having at its upper terminal a laterally or transversely arranged bearing 11 and a depression 12 formed inwardly of the said bearing and on each side of the projection 13 centrally formed on the handle. The depressions 12 have pivoted therein the pawls 14 which are normally forced toward the bearing 11 by

45 the spring 15 which is mounted in the opening 16 formed transversely in the projection 13 and operate transversely against the inner terminals of the pawls 14. The stationary jaw indicated generally as "A" is pivotally mounted upon the bearing 11, as will 50 hereinafter be more fully described. This stationary jaw comprises a shank 17 having a longitudinal dovetailed groove 18 formed therein. A slot 19 is arranged obliquely across the face of the shank 17 and

provides a means whereby the movable jaw may be secured to the stationary jaw and operate in the slot 18. A transverse head 20 is formed at the upper terminal of the shank 17 and forms one of the jaws of the wrench, while a transverse bearing 21 is similarly formed at the lower terminal of the shank 17, said bearing forming a support for the movable jaw, as will hereinafter be more fully described.

60 The shank 17 has formed thereon a suitable ratchet wheel 22, which, when the jaw is mounted upon the bearing 11 of the handle 10, operates in a circular depression 23 formed inwardly of the bearing 11. When 70 the jaw "A" is in its operative position the pawls coöperate with the ratchet wheels 22 and retain the jaw "A" in a rigid and adjusted position. The terminal of the bearing 11 is provided with an interiorly threaded opening 24, in which a screw is placed for the retaining of the jaw "A" upon the 75 said bearing.

75 The bearing 21 of the stationary jaw has swiveled therein a screw 25 which is operated by the finger piece 26 formed adjacent to the bearing 21. This screw projects into the movable jaw 27, and by the operation of said screw said movable jaw 27 is operated longitudinally as desired. A dovetailed 80 projection 28 is formed on the rear surface of the movable jaw 27, and is adapted to reciprocate in the slot 18 of the stationary jaw "A," said projection being inserted in the groove 18 by means of the obliquely arranged slot formed therein.

85 In order to provide a means whereby the pawls may be restrained from movement, a slot 29 is formed in each side of the handle 10 adjacent to the depressions 12, and has 90 slidably mounted therein a stop or finger piece 30, said stop or finger piece adapted to rest against the coöperative pawl and secure the same from movement.

95 From this construction it will clearly be seen that by sliding the stops 30 in the slot 29 and exerting a pressure upon the lower terminals of the pawls 14, the stationary jaw "A" may be swung about its pivotal point to any desired angle. It will further 100 be understood that by the rotation of the screw 25 the position of the movable jaw 27 is regulated. If so desired, the said movable jaw can readily be removed from the stationary jaw by primarily removing the 105

screw 25 and partially twisting said jaw until the projection 28 coincides with the opening 19 and the groove 18.

Having thus fully described our invention, 5 what we claim as new, and desire to secure by U. S. Letters Patent is:

1. A wrench comprising a handle, a bearing mounted on said handle, a stationary jaw carried by said bearing, a shank formed 10 on said jaw, said shank having a groove therein and an oblique slot crossing said groove, a movable jaw slidably mounted in said groove and means to adjust said jaws with relation to one another.
- 15 2. In a wrench comprising a handle, a

jaw mounted thereon, a shank formed on said jaw, said shank provided with a longitudinal dove-tailed groove and a slot extending obliquely across the groove, a movable jaw provided with a dove-tailed projection 20 thereon adapted to be inserted in the oblique slot and slide in the dove-tailed groove, and means for operating the sliding jaw.

In testimony whereof we affix our signatures in presence of two witnesses.

HARRY B. KUNTZ.
GEORGE T. KUNTZ.

Witnesses:

C. B. GALLEY,
A. M. JEWALL.
